UNITED STATES PATENT OFFICE.

BERNT GARLLUS, OF DETROIT, MICHIGAN, ASSIGNOR TO ALEXANDER J. McDONOUGH,
OF DETROIT, MICHIGAN.

BOILER-FEED-WATER REGULATOR.

Application filed August 18, 1927. Serial No. 213,856.

The invention relates to boiler feed water regulators of that type comprising an expansible tube arranged in an inclined position and connected at its opposite ends respectively with the water space and the steam space of the boiler. With such a construction variations in the water level will correspondingly vary the relative lengths of the portions of said tube exposed respectively to contact with the water and with the steam. As the water, through loss of heat by radiation, is always at a lower temperature than the steam, such variation in level will cause either expansion or contraction in the total length of the tube which may be utilized for operating the regulator.

The present invention relates to the construction of mechanism by which this expansion and contraction of the tube is transmitted to the valve or other controlling means for the water feed and the invention therefore consists in the novel construction of this mechanism and the peculiar combination of the same with the actuating expansible tube as hereinafter set forth.

In the drawings:

Figure 1 is a perspective view of my improved regulator operating mechanism.

Figure 2 is a perspective view of the bracket which constitutes a portion of the frame and the bearing for the rock lever.

Figure 3 is a perspective view of the rock lever and

Figure 4 is a sectional elevation showing the rock lever with its knife edge bearing and in operative relation to the expansible tube.

As shown in Figure 1, A is the expansible tube formed of any suitable material such as copper having a relatively high coefficient of expansion. This tube is mounted in a frame one end of which is formed by a bracket B having a flange C connected by rods D to a similar bracket or anchorage (not shown).

One end of the tube is connected to this fixed anchorage by any suitable means (not shown) while the other end of the tube is free to slide through a bearing aperture E in the flange C. The tube may also be supported at one or more intermediate points by passing through bearings in cross bars F mounted on the bars D. Thus when so mounted the end of the tube A which projects beyond the flange C is freely movable under force of expansion and contraction.

To obtain accurate regulation it is highly

desirable that the mechanism for transmitting movement of the tube to the regulator should be as frictionless as possible. At the same time it is desirable to avoid any delicacy in construction which would render the apparatus liable to injury in shipment or installation. This I have accomplished through the use of a rock lever directly actuated by the expansible tube and provided with a knife edge bearing for reducing friction to the minimum. However, this knife edge bearing is only subjected to the stresses incident to the operation of the regulator while other stresses incident to the handling of the apparatus are taken care of by more substantial bearings.

In detail the bracket beam has mounted thereon an outwardly extending pin or shaft G having a V-shaped groove G' formed in one side thereof. H is a rocker member having a hub portion I which is sleeved over the pin G and also provided with a knife edge bearing member J projecting inward and engaging the groove G'. For convenience in manufacturing, the knife edge bearing member J is mounted within a length of tube K being secured thereto by rivets L at one or more points in its length. The tube K is then inserted in the hub I and a projecting end of the rivet L engaging a recess M in said hub serves to hold the members K and J against rotation in the hub. The member H is preferably a casting and is provided with the oppositely extending arms H', H² recessed to receive the pin of a bar N which forms the lever arm. This bar may be bolted to one or the other of the recessed arms according to which direction it is desired to have it extend. The casting H is also provided with projecting ears H³, H⁴ forming the mounting for a pin O which constitutes in effect a bell crank arm for the lever N. Thus when the member H is placed in engagement with pin G the pin O will be arranged in alignment with the projecting end of the tube A. Said end of the tube is connected with an angle fitting P through which the tube is coupled by a pipe connection shown in dotted lines at Q with the steam space of the boiler. The fitting P has an outwardly projecting lug P' adapted to bear against the pin O, the arrangement being such that when the tube A expands, the lug P' will move outward, the pin O rocking the member H and the lever arm N. This rocking movement is communi-

cated by a connecting rod or link R to the valve or other controlling mechanism (not shown).

In assembling the parts of the mechanism just described the pin G which is secured by a set screw S to the bracket B is so arranged that the V-shaped groove G' is at a predetermined angle. This angle is such that the resultant of the force longitudinally of the tube A and the force of gravitation operating upon the lever arm N will take a direction along the central plane of the groove G'. The angle of the knife edge member J being less than the angle of the groove G' and being also centrally arranged in said groove, it is evident that the movement of the tube A in expanding or contracting will rock the member H and lever arm N with the bearing solely upon the knife edge J. Thus the factor of friction is very small and any movement of the tube A is instantaneously transmitted through the lever and connecting link R to the regulator. On the other hand any other force which may be accidentally applied to the lever or to the member H will be resisted by the sleeve K which has only a very slight clearance from the pin G.

In installing regulators upon boilers they must be variously located to suit convenience and space limitation. My improved mechanism provides for such variation, first in that the rocker arm N may be attached to the member H to extend in either direction; second, the bracket B is provided with two socket bearings G², G³ for alternatively receiving the pin G, one of these sockets being above the center line of the tube A and the other below the same; third, the set screw S permits of arranging the groove G' at any desired angle; fourth, the tube K may be rotatively adjusted within the hub member I by disengaging the rivet L from the recess M and reengaging it in one or more auxiliary recesses M'. These various adjustments enable the workmen installing the apparatus to meet almost any condition encountered. The bracket B is provided with a base flange B' having a slot B² therein for receiving the clamping bolts that secure the bracket to the boiler wall or front.

50 What I claim as my invention is:

1. The combination with a longitudinally expansible actuating member, of a frame in which said member is mounted having a bracket at one end thereof providing a bearing for the sliding engagement of the free end of said expansible member, a pin alternatively engageable in sockets in said bracket member respectively above and below the axis of said expansible member to extend in a direction transverse to said axis, a rockable member having a hub portion sleeved upon said pin, a bell crank arm projecting from said hub and engageable with the free end of said expansible member and arms projecting oppositely from said hub in a plane trans-

verse to the plane of said bell crank arm and an extension lever arm secured alternatively to said oppositely extending arms.

2. The combination with an expansible tube having its opposite ends connected respectively to the water and to the steam space of a boiler, of a bracket forming the bearing for the free end of said tube, a bell crank lever for transmitting movement of said tube to the regulator to operate it, and a knife edge bearing for said bell crank lever on said bracket.

3. The combination with a longitudinally expansible member, of a bracket forming a bearing for the free end of said member, a pin projecting from said bracket, a bell crank lever having a hub sleeved upon said pin and arranged to have one arm in alignment with said expansible member and a knife edge bearing between said hub and pin arranged to receive the normal actuating thrust of said expansible member.

4. The combination with an expansible member, of a bracket having an apertured flange forming the bearing for the free end of said expansible member, a pin projecting transversely from said bracket and having a V-shaped groove therein, a rockable bell crank member having a hub portion loosely sleeved on said pin, and a knife edge bearing projecting inward from said hub to engage said V-shaped groove and to take the thrust normally communicated to said bell crank from said expansible member.

5. The combination with a supporting bearing of a pin projecting therefrom having a V-shaped groove therein, a bell crank lever provided with a hub sleeved upon said pin with a clearance, a knife edge member secured to and projecting inward from said hub into engagement with said V-shaped groove adapted to take the normal thrust of actuation applied to said bell crank lever, said pin holding said bell crank from axial displacement.

6. The combination with a bearing member, of a pin mounted thereon and projecting laterally therefrom having a V-shaped groove extending longitudinally thereof, a rockable member provided with a hub sleeved on said pin with a clearance, a knife edge bearing projecting laterally inward from said hub into engagement with said V-shaped groove, said knife edge member being of a radial length to normally hold said hub out of peripheral contact with said pin.

7. The combination with a bearing member, of a pin mounted thereon and provided with a longitudinally extending V-shaped groove, a rockable member having a hub sleeved on said pin, a bushing for said hub having a clearance on said pin and provided with an inwardly extending knife edge bearing for engaging said V-shaped groove, said bearing being of a radial length to normally hold said bushing out of peripheral contact with said pin, means

for locking said pin in different positions of rotative adjustment on said supporting bearing and means for locking said bushing in different positions of rotative adjustment in said hub.

8. The combination with an expandible member, of a bracket, a pin projecting from said bracket, a lever having a hub sleeved upon said pin and a portion arranged in the path 10 of movement of said expandible member, and a knife edge bearing between said hub and pin arranged to receive the normal actuating thrust of said expandible member.

9. The combination with a bracket member, of an adjustable pin mounted thereon and provided with a seat, a rockable member having a hub sleeved on said pin and provided with an adjustable knife edge bearing for engaging said seat, means for locking said pin in different positions of rotating adjustment on 20 said supporting bracket, and means for locking said knife edge bearing in different positions of rotative adjustment in said hub.

In testimony whereof I affix my signature.

BERNT GARLLUS.
